UNITED STATES PATENT OFFICE.

PHILIP MÜLLER, OF NEW YORK, N. Y.

FILTER.

SPECIFICATION forming part of Letters Patent No. 395,291, dated December 25, 1888.

Application filed October 27, 1888. Serial No. 289,350. (No model.)

To all whom it may concern:

Be it known that I, PHILIP MÜLLER, a citizen of the United States, residing at New York, in the county and State of New York, 5 have invented new and useful Improvements in Filters, of which the following is a specification.

This invention relates to a filter which is intended particularly for drawing lager-beer 10 from the fermenting-casks into kegs; but my filter can also be used for other liquids under pressure.

The peculiar and novel construction of my filter is pointed out in the following specification and claim, and illustrated in the accompanying drawings, in which—

Figure 1 represents a longitudinal central section. Fig. 2 is a transverse section in the plane $x x$, Fig. 1.

20 Similar letters indicate corresponding parts. In the drawings, the letter A designates a case which is by preference made cylindrical and of metal sufficiently strong to withstand the pressure to which it may be exposed. When the filter is to be used for beer, I make the case of sheet-copper, coated on its inner surface with tin, so that it is not liable to corrode by the action of the beer. On one end of this case is firmly secured a head, B, 25 which is provided with an opening, a , and with a suitable coupling, so that it can be readily connected to the liquid-supply pipe. On the opposite end of the head is firmly secured the head C, which is provided with an opening, b , and with a screw-nipple, c , so that the liquid-discharge pipe can be readily connected to the same. Both heads are secured to the case in such a manner that they can be readily removed in order to obtain access 30 to the interior of the case. Suitable packing-rings, d e , insure tight joints between the heads and the case.

D is a strainer, which is made of foraminous sheet metal, of sufficient strength to withstand the pressure to which it may be exposed. It is closed at the end facing the supply-head B and open at its opposite end, which is firmly secured to the discharge-head C. For the purpose of making the connection between 45 the strainer and the discharge-head C, the latter is provided with an internal flange, f ,

having a screw-thread on its inner surface, and the strainer is provided at its open end with an external screw-thread to engage the thread of the flange f . A packing-ring, g , insures a tight joint. 55

Over the strainer D is placed a filtering-bag, E, which is composed of an inner layer of perforated sheet metal or wire-gauze, and of an outer layer (one or more) of cloth, felt, 60 or other equivalent material, and which is closed at its bottom. In the example represented in the drawings I have shown two filtering-bags, one over the other, but in some cases a single filtering-bag will be sufficient. 65 The filtering-bag is retained in position on the strainer by a clamping-ring, h .

The liquid to be filtered is drawn from receptacles—such, for instance, as fermenting-casks of lager-beer—under a pressure of from 70 five to ten pounds to the square inch, and as it enters the case A through the supply-opening a , it fills the annular space between the outer surface of the filtering-bag and the inner surface of the case, and it is gradually 75 forced through the different layers of the filtering-bag into the interior of the strainer D, whence it escapes through the discharge-opening b . It is obvious that the impurities contained in the liquid as the same enters the 80 case A are retained by the filtering bag or bags, and the liquid which discharges through the opening b is practically free from impurities. If the filtering bag or bags have become 85 surcharged with impurities, they can be readily removed from the case A and cleansed by washing or otherwise.

In using my filter for lager-beer I have found that when the communication between the case A and the fermenting-cask is first 90 opened the filter becomes filled with foam, and I have provided the case C with a cock, F, which at the beginning is opened until no more foam appears.

What I claim as new, and desire to secure 95 by Letters Patent, is—

The combination of the casing A, having at one end the supply-head B, provided with the receiving-opening a , and at the opposite end the discharge-head C, provided with the discharging-opening b , the tubular strainer D, closed at one end opposite the receiving-open-

ing in the supply-head and having its other end open and secured to the discharge-head around the discharging-opening therein, and a filtering-bag, E, inclosing the sides and the 5 closed end of the tubular strainer, secured at its open end upon the strainer around its open discharging end and comprising a closed end lying against the closed end of the tubular strainer directly opposite the receiving-open-

ing of the supply-head, substantially as described.

In testimony whereof I have hereunto set my hand and seal in the presence of two subscribing witnesses.

PHILIP MÜLLER. [L. S.]
